(57) **CLAIM**

The ornamental design for a shaver handle, as shown and described.

DESCRIPTION

FIG. 1 is a back perspective view of an ornamental design for a shaver handle design according to the present invention;

FIG. 2 is a front perspective view thereof;

FIG. 3 is a top view thereof;

FIG. 4 is a bottom view thereof;

FIG. 5 is a right side view thereof;

FIG. 6 is a left side view thereof;

FIG. 7 is a back view thereof; and,

FIG. 8 is a front view thereof.

All portions shown in broken lines including those shown in the gripping areas are environmental and illustrative only and form no part of the claimed design.
